Inventor

United States Patent Office.

WILLIAM A. SPRING, OF TITUSVILLE, PENNSYLVANIA.

Letters Patent No. 93,761, dated August 17, 1869.

IMPROVEMENT IN ADJUSTABLE CLUTCHES FOR LIFTING WELL-TUBING.

The Schedule referred to in these Letters Patent and making part of the same.

To all whom it may concern:

Be it known that I, WILLIAM A. SPRING, of the city of Titusville, county of Crawford, and State of Pennsylvania, have invented a certain new and improved Adjustable Tubing-Clutch; and I do hereby declare that the following is a full, clear, and exact description thereof, reference being had to the accompanying drawings, which form a part of this specification.

The object of my invention is to provide a clutch for lowering and raising tubing in artesian wells, which shall be sufficiently adjustable to fit any ordinary-sized well-tubing, and to adjust itself to any irregularities upon the edges of the collars or thimbles, while it shall be durable, readily attached and detached, and secure in its hold upon the tubing.

In the drawings—

Figure 1 represents a front view or elevation of my improved clutch;

Figure 2 is an edge view of the same; and

Figures 3 and 4 are horizontal sections, taken on lines A B and C D.

a a are vertical jaws, curved and connected at their upper ends by the double-jointed hinge b.

Said jaws are also curved inwardly at their lower ends, and forged into the proper form to fit and grip a tube, say, of three inches diameter, or thereabouts, all as shown, the gripping-edge a', of the jaws, being preferably tipped with steel.

c is a central bolt, having an eye at its upper end for the attachment of a rope, and connected at its lower end with the jaws a a, by means of the links d d, the jaws being pivoted to the hinge b, and the links d d to the jaws and bolt c, as shown.

The hinge b and the upper ends of the jaws are arranged to embrace the bolt c, and allow it to play freely through or between them.

In the drawings, the blue lines represent a piece of tube with thimble or collar attached.

In using this clutch, the ends a' of the jaws are passed over the collar or other projection upon the tube; and upon tightening the rope e, the weight or strain upon the jaws is transmitted through the pivoted links d d to the bolt c, and, under the described arrangement of parts, any weight or strain upon said bolt tends to draw the jaws together, so that the greater the weight of the tubing, the firmer it is gripped and held between them.

Upon slackening the rope e, the jaws a a are instantly spread, and the clutch detached.

When in use, a small pin may be loosely inserted in the bolt c, above the hinge b, to prevent the detachment of the clutch by any accidental slackening of the rope.

When desirable, a swivel may be attached to the upper end of the bolt c.

By arranging the bolt c to embrace the hinge b, instead of passing through it, a single pivot will suffice to connect the upper ends of the jaws a a, but I prefer the arrangement shown, as it allows of the separate vertical adjustment of each jaw to fit any irregularities upon the edge of the collar.

I am aware that grappling-tongs have been constructed, in which the parts were so arranged that the firmness of the grip was increased by and in proportion to the weight of the article to be lifted, and I make no broad claim to such an arrangement; but

What I claim as my invention, and desire to secure by Letters Patent, is—

An adjustable tubing-clutch, with hinged jaws a a, hinge b, links d d, and central bolt c, all combined and arranged substantially as and for the purposes set forth.

WILLIAM A. SPRING.
